UNITED STATES PATENT OFFICE.

HARRY A. KAUFMANN, OF KANSAS CITY, MISSOURI, ASSIGNOR TO HENRIETTA S. KAUFMANN, OF MINNEAPOLIS, MINNESOTA.

DISHWASHER.

Application filed November 22, 1920. Serial No. 425,759.

To all whom it may concern:

Be it known that I, HARRY A. KAUFMANN, a citizen of the United States, residing at Kansas City, in the county of Jackson and State of Missouri, have invented 5 certain new and useful Improvements in Dishwashers; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification. 15

This invention relates to dish washing machines and the primary object thereof is to provide a dish washing machine so constructed that the cleansing liquid or suds 20 will be distributed about the container and over the dish racks above the normal level of the cleansing liquid so that the foreign matter will be efficiently removed from the dishes and gravitate to the bottom of the 25 receptacle.

There is a material advantage in arranging the dish racks above the normal level of the cleansing fluid because if the racks are submerged, the solid particles will adhere to the dishes and it will be impossible 30 to rinse them properly. By providing the racks above the normal water level and providing a distributor, the cleansing fluid can be thrown over the dishes by the distributor 35 in a manner to remove the foreign matter therefrom and in this way, the dishes will be automatically drained, leaving them free from extraneous matter, as will be apparent by reference to the following description 40 and as the nature of the invention is better understood.

It is the purpose of my invention to provide means whereby the dishes may be not only efficiently cleaned but whereby they 45 may be dried quickly and to this end I prefer to direct air, preferably heated, over the dishes to evaporate the moisture therefrom. The air may be directed centrally through the bottom of the receptacle, from which 50 point it may be distributed over the dishes.

An air column may also be employed for agitating the cleansing fluid within the receptacle; that is, an incoming column of air can be directed centrally through the liquid column or body so that it will be agi- 55

tated enough to be thrown in streams above the normal level of the liquid, there being a distributor in the path of the agitated streams, which will throw the water or liquid horizontally or substantially so, preferably in radial stream lines, against the sides of the racks and against the dishes contained therein.

After the dishes are washed, the water can be drained therefrom and the air introduced to quickly dry them, as will be clearly apparent by reference to the following description taken in connection with the accompanying drawings, in which

Fig. 1 is a perspective view of a dish 70 washing machine constructed in accordance with my invention.

Fig. 2 is a vertical, longitudinal, sectional view through the same.

Fig. 3 is a detail perspective view of the 75 distributor.

Fig. 4 is a sectional view through the air conduit, showing an automatic circuit breaker movable in response to air pressure, and

Fig. 5 is a sectional view through a part 80 of the distributor, showing the manner of connecting it to the post which supports it.

In the illustrated embodiment of my invention I have shown a container, receptacle 85 or tank 1, which is preferably circular and provided with a conical bottom 2, having a valved outlet 3 and an open inlet 4, the inlet communicating with a conduit 5, connected to an air impeller or pump 6, the impeller 90 element of which is adapted to be driven by any suitable means as, for example, an electric motor 7.

The impeller casing 8 is provided with a neck or tubular portion 9, projecting 95 through an opening 10 in the wall of the receptacle 1 and said tubular portion is adapted to receive a threaded washer or nut 11 on the inside of the receptacle 1 whereby the casing 8 will be rigidly attached to the receptacle 1. The tubular portion 9 constitutes an inlet for the impeller casing 8, the outlet communicating with the tube 5 to direct a column of air through the inlet opening 4 of the receptacle 1.

A bracket 12 carried by the bottom of the receptacle 1 supports a tubular standard 13, adapted to receive a post 14, extending in axial alignment with the conical bottom 2, the end of the post being provided with a 110

knob or ball 15, which fits in a pressed-in recess 16 on a distributor disk 17. The distributor disk is concavo-convex, preferably in the shape of a cone and has a plurality 5 of faces 18, against which the air or water or both may be directed so that the fluid directed against the under or convex side of the distributor will be deflected in substantially horizontal lines against the dishes in 10 the dish rack or racks.

The under side of the disk 17 carries a washer or guard 19, which fits about the head 15 loosely so that the disk 17 may have a wobbling, rotative movement about the 15 post 14, the general motion of the deflector or distributor being indicated in dotted lines in Fig. 3.

The receptacle 1 carries one or more dish racks, there being two shown in the drawings and designated 20 and 21, the former 20 preferably being for dishes and the latter for glassware. The dish racks may be conveniently supported within the receptacle in any well known manner. The lower dish 25 rack 20 preferably has handles 22 and 23 which may be extended, as shown in Fig. 1, to hold the rack 20 supported upon the top 24 of the receptacle 1 so that the dishes may be conveniently accessible or for permitting the rack to be supported while the 30 dishes are being placed therein.

Above the dish racks is a conical deflector 25, which is secured to the top or cover 26 by brackets or straps 27 and 28, the cover 35 26 being hinged at 29 to the top 24, as clearly seen in Fig. 2.

The deflector 25 is for the purpose of directing cleansing water or suds which may splash above the rack 21 back into the receptacle and for the purpose of preventing the cleansing liquid being discharged through the top or into the exhauster space 30 between the deflector and the cover 26.

There is a central, conical opening 31 in 45 the center of the deflector 25, which permits air to be exhausted from the receptacle into chamber 30, into the inlet or the exhauster casing 8 and back into the inlet 4 of the receptacle. There is also a blow-off valve 50 32 in the cover 26, which may be operated when the pressure within the receptacle 1 reaches a determined degree as it may, due to steam being generated by the heater 33 carried by the conical portion of the receptacle 1 and normally below the liquid level in 55 the container.

The heater is provided with a contact bracket 34 on the outside of the receptacle 1, adapted to receive an electric plug connection 60 35 from a conductor 36, receiving its power from a suitable source connected to the conductor cord 37, which carries not only the conductor cable 36 but a cable 38, connected to the fan motor 7. The conductor wires 39 and 40 for the conductor cable 36

terminate in two contacts 41 and 42, extending within the vertical leg of the conduit 5 and beneath the contacts 41 and 42 is an automatic circuit closer, illustrated as a disk 43, pivoted within the conduit at 44 and 70 carrying a counter-weight or bar 45 which constitutes a contact bar for bridging the gap between contacts 41 and 42. Therefore, when the current is turned on and the fan is set in motion, the air pressure will swing 75 the disk or damper 43 out of obstructing position, causing the bar 45 to bridge the contacts 41 and 42 and effecting a series connection between the conductor wire 39, contacts 41 and 42 and the heat element 33, the conductor wire 40' being the return conductor 80 as will be well understood.

The heating element may be a ring of copper tubing, in which the heating element 85 may be positioned, the ring being sealed against action of the water in which it is submerged.

Therefore, when the current is turned on, the impeller fan will operate, causing the 90 circuit for the heater to be closed by moving the bar 45 against contacts 41 and 42 so that the heating element of the heater 33 will be energized to raise the temperature of the water in which it is submerged. At the same time air will be exhausted from 95 the chamber 30 through the fan casing 8 and conduit 5 and through the inlet 4, causing the cleansing liquid to be agitated sufficiently to force a column of water up against the deflector or distributor disk 17. 100 The polygonal faces 18 of the disk will receive the column of water in such a manner that there will be a tendency to tilt the disk so that it will wobble about its axis, throwing a somewhat irregular spray or volume 105 of water against the dishes in substantially horizontal, radial lines, the water being directed against the dishes with sufficient force to remove objectionable matter carried thereby and as the water flows over the 110 dishes, it will automatically rinse them, causing the solid particles to gravitate to the bottom of the receptacle 1, from which point they may pass out through the discharge 3 when the operator presses upon the peddle 115 46 of the lever 47, fulcrumed at 48 to one of the standards 49, it being understood that the opposite end of the lever is connected to the spring-retained valve stem 50.

The standards 49 are preferably received 120 in tubular sockets or members 51, which are supported by the receptacle and its top 24, the standards being vertically adjustable and when adjusted, they are adapted to be held in proper position by the set screws 52, 125 it being understood that the standards 49 can be telescoped in 51 to facilitate shipping as well as to permit the receptacle to be raised and lowered for the purpose of convenience or for leveling the device. 130

The top 24 also preferably carries hinged leaves or shelves 53 and 54, which are adapted to be held in horizontal positions on the top 24 to constitute a part of a table to hold dishes or the like. These leaves, however, 5 may be dispensed with if desired.

It will be apparent from the foregoing that when the parts are properly assembled with the dishes in their rack and the cleansing 10 liquid below the rack so that the dishes will not be submerged, the motor can be operated so that a current of air or air and liquid will be driven against the deflector of distributor disk 17, which will direct the 15 liquid over the dish racks and the dishes contained therein to remove objectionable matter.

After the device has operated a sufficient 20 length of time to effect the proper cleansing of the dishes, the foot lever 46 can be operated to drain off the cleansing water, it being generally desirable to first shut down the motor, and after the liquid has been drained off, the motor can again be started up so 25 that a dry blast of air will be directed into the receptacle to evaporate any moisture therein and thereby dry the dishes, it being understood that when the water is drained off, the air will pass over the heater 33 to 30 be heated preparatory to contacting with the dishes.

In actual practice I have found that a device constructed in accordance with my invention is efficient and easily operated.

What I claim and desire to secure by Letters-Patent is:

1. A dish washer comprising a liquid container, a dish rack within the container above the normal liquid level therein, means for directing the liquid centrally and upwardly 40 from the lower portion of the container, and a rotative, wobbling liquid distributor above the normal level of the liquid for directing the liquid toward the wall of the container.

2. A dish washer comprising a liquid container, a dish rack within the container above the normal liquid level therein, means for directing a column of air through the liquid to elevate a portion thereof above the normal liquid level, and means for distributing 45 the elevated liquid about the container.

3. A dish washer comprising a circular container having a hopper bottom provided with an orificed extension and having a discharge opening in the bottom of the extension, a tube communicating with the orificed extension, an air impeller having an exhauster end connected to the top of the container and discharging into the tube, a deflector between the bottom of the container 55 and the exhauster end of the impeller, a liquid deflector between the first named deflector and the bottom of the container, the axis of which is in line with the axis of the container, and means for actuating the impeller.

In testimony whereof I affix my signature.
HARRY A. KAUFMANN.
